(74) Attorney, Agent, or Firm — Sand, Sebolt & Wernow Co., LPA

(57) **CLAIM**

The ornamental design for a fence stop, as shown and described.

DESCRIPTION

FIG. 1 is a front, top, left side isometric perspective of the fence stop in accordance with my design.

FIG. 2 is a rear, top, right side isometric perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan thereof.

The broken lines illustrate portions of the fence stop which form no part of the claimed design.

1 Claim, 4 Drawing Sheets(56)
